UNITED STATES PATENT OFFICE.

JOHN COLLIS, OF DES MOINES, IOWA, ASSIGNOR OF ONE-HALF TO WILLI P. COLLIS, OF NEW YORK, N. Y.

AUTOMATIC PRESSURE-REGULATOR.

SPECIFICATION forming part of Letters Patent No. 308,030, dated November 11, 1884.

Application filed December 17, 1883. (No model.)

To all whom it may concern:

Be it known that I, JOHN COLLIS, of Des Moines, in the county of Polk and State of Iowa, have invented an Automatic Pressure-Regulator, of which the following is a specification.

My invention is a simple method and attachment for maintaining a uniform pressure of steam in the cylinder of a pump, drying-cylinders, evaporating pans, and steam-heating apparatus, as required to operate a pump at any rate of speed desired, or to preserve an even temperature in a room or building while the pressure in the generator or source of supply of steam and power varies.

Heretofore a cylindrical valve, a piston, a lever of the second order, and an adjustable weight have been combined with a tube to regulate steam-pressure.

My attachment consists in the construction and combination of a distinct cylinder, an auxiliary tube, a piston, a lever of the first order, and a sliding cut-off valve, as hereinafter fully set forth, in such a manner that irregular pressure from the boiler will alternately raise and lower the piston and move the sliding valve in reverse ways, so that the volume of steam allowed to pass will be diminished under heavy pressure and increased under light pressure, to equalize the pressure where the steam is applied and where uniformity of pressure is to be maintained.

Figure 1 of my accompanying drawings is a longitudinal section of my device. Fig. 2 is a transverse section of the distinct cylinder formed integral with a tubular section. Fig. 3 is a vertical sectional view of the sliding cut-off valve.

Jointly considered, these figures clearly illustrate the construction, application, and operation of my complete invention.

A represents a section of a steam-conveying tube that may vary in size, as desired, connected with a globe-valve, B, of corresponding size.

C is a short tube on the opposite end of the valve and tube section B.

D is a short tube that has a cylinder, f, formed integrally therewith.

G represents an auxiliary tube about one-fourth as large in diameter as the tubes A and C, connected at one end with the tube A or the generator, and at its opposite end with the cylinder f in the tube D.

B² is a globe-valve connected with the auxiliary tube G.

h is a piston in the cylinder f, and the top of its stem i is flexibly connected with a beam and lever of the first order, k, which lever is supported upon a post and fulcrum, l, that is fixed on top of the tube D.

Heretofore a lateral branch on a tube has been used as a cylinder for a piston; but a distinct cylinder extending through a tube transversely in such a manner as to allow steam to pass through the tube without entering the cylinder is novel and greatly advantageous.

m is a valve-chamber and tube-section connected with the end of the tube D.

m' is a cylinder extending down from the valve-chamber m.

A² represents a tube connected with the chamber m, to conduct steam to a pump-piston, drying-pan, radiator, or wherever it is to be applied and utilized.

n is an extension on top of the valve-chamber and tube-section m, that forms a bearing for a sliding valve or cut-off, o.

o' is a piston extending down from the valve o into the cylinder m'.

r is a cap fixed on top of the extension n, into which the valve o ascends in its upward motion, and through the extended top r' thereof or a stuffing-box fixed thereto the valve-stem o' passes upward to be flexibly connected with the short arm of the beam or lever k by means of a link, s, or in any suitable way, so that the valve and stem will be moved vertically by the vibratory motions of the horizontal lever k.

w is an adjustable balance-weight on the beam or lever k.

In place of connecting the auxiliary tube G with the cylinder f, to operate the piston h, and thereby the cut-off valve o, by means of the lever k, I connect the auxiliary tube direct with the valve-chamber m and cylinder m', as indicated by dotted lines in Fig. 1, and reverse the

position of the lever *k*, to thereby operate the valve *o* to regulate the pressure in the tube A^2 by duplicating the parts *n* and *r* and placing them between the cylinder *m'* and the tube-section A^2 , so that the position of the valve will also be reversed when the position of the lever is reversed and the lever changed from a lever of the first order to a lever of the second order. In some places there is not sufficient room to extend the lever *k* toward the valve *B*, and hence the necessity for reversing the position of the lever and connecting the auxiliary tube direct with the cut-off or regulating-valve *o*.

15 In the practical operation of my device and method of maintaining a uniform pressure in one portion of a steam-conveying tube while it varies in another part, I simply adjust the balance-weight *w* on the lever and scale-beam *k* to the figure on the scale that indicates the uniform pressure desired, and then open the valve *B* to allow the steam to pass through the main tube, and also into the auxiliary tube *G*. If only twenty pounds pressure is to be maintained at the point of delivery and forty or eighty pounds is received from the generator, the piston connected with the beam and lever *k* will rise and cause the valve *o* to descend to diminish the opening in the valve-chamber and tube-section *m*, as required to diminish the flow and volume of steam and maintain a uniform pressure in that part of the tube A^2 that extends from the regulating-valve *o* to the pump-cylinder, drying-pan, or radiator where the steam is to be utilized. Any desired uniform pressure may thus be readily maintained by means of an auxiliary tube, a regulating-

valve, and suitable valve-operating mechanism; and by using a vertically-sliding valve that descends to the bottom of the continuous tube water will not be retained in the tube to obstruct the passage of steam.

I claim as my invention—

1. A pressure-regulator consisting of the following-named elements, to wit: a steam-conveying tube, an auxiliary tube, a cylinder, a piston, a valve-chamber in the main tube, a valve adapted to enlarge and diminish the passage in the main tube, a lever, and an adjustable weight, arranged and combined to operate in the manner set forth, for the purposes specified. 45

2. A tube-section having a distinct and complete open-ended cylinder, *f*, formed integral therewith, and extending through its diameter, for the purposes specified. 55

3. The combination of a tube-section, *A*, a valve, *B*, a tube-section having a cylinder extending at right angles therewith, a piston, a lever, an auxiliary valve, the continuous tube, 60 and an auxiliary tube, *G*, to operate in the manner set forth, for the purposes specified.

4. The combination of a tube-section, *A*, a valve, *B*, a cylinder, *f*, and piston *h* *i*, a tube-section and valve-chamber, *m*, having a cylinder, *m'* *n* *r*, a valve, *o*, having a piston, *o'*, a scale-beam and lever, *k*, fulcrum *l*, a balance-weight, *w*, and an auxiliary tube, *G*, to operate in the manner set forth, for the purposes specified. 65

JOHN COLLIS.
